(57) **CLAIM**

The ornamental design for a firework lamp, as shown and described.

DESCRIPTION

FIG. 1 is a first perspective view of a firework lamp showing my new design;

FIG. 2 is a second perspective view thereof;

FIG. 3 is a front view thereof;

FIG. 4 is a back view thereof;

FIG. 5 is a left side view thereof;

FIG. 6 is a right side view thereof;

FIG. 7 is a top view thereof;

FIG. 8 is a bottom view thereof; and,

FIG. 9 is an enlarged view of the selected portion 9 in FIG. 2.

The dash-dash broken lines shown in the drawings depict portions of the firework lamp that form no part of the claimed design. The dot-dash broken lines in FIGS. 2 and 9 illustrate the periphery of the enlarged views of the firework lamp and form no part of the claimed design. The firework lamp is shown with symbolic breaks in its length. The appearance of any portion of the firework lamp between the break lines forms no part of the claimed design.
